Primary Examiner — Ricky Pham(74) *Attorney, Agent, or Firm* — Taylor J. Ross(57) **CLAIM**

The ornamental design for a food bin with cutting board, as shown and described.

DESCRIPTION

This application is related to co-pending application Ser. No. 14/458,706, filed Aug. 13, 2014, and is incorporated herein by reference.

FIG. 1 is a top, front and left side perspective view of a food bin with cutting board showing my new design;

FIG. 2 is top, front and left side exploded view of the food bin with cutting board shown in FIG. 1;

FIG. 3 is a bottom, front and right side exploded view thereof; FIG. 4 is a top plan view thereof;

FIG. 5 is a bottom plan view thereof;

FIG. 6 is a front elevation view, the rear elevation being identical thereto;

FIG. 7 is a right side elevation view, the left side being identical thereto;

FIG. 8 is a cross-sectional view taken along line 8-8 of FIG. 4;

FIG. 9 is a cross-sectional view taken along line 9-9 of FIG. 4; and,

FIG. 10 is a detailed perspective view from portion 10 in FIG. 2.
